US00D753675S

(12) **United States Design Patent**
Yang et al.

(10) **Patent No.:** US D753,675 S
(45) **Date of Patent:** ** Apr. 12, 2016

(54) **MULTIMEDIA TERMINAL WITH
GRAPHICAL USER INTERFACE**

(71) Applicant: **LG ELECTRONICS INC.**, Seoul (KR)

(72) Inventors: **Jeong Hwa Yang**, Seoul (KR); **Hye Soo Kong**, Seoul (KR); **Jin A Lee**, Seoul (KR); **Eun Gyeong Gwon**, Seoul (KR)

(73) Assignee: **LG Electronics Inc.**, Seoul (KR)

(**) Term: **14 Years**

(21) Appl. No.: **29/491,500**

(22) Filed: **May 21, 2014**

(30) **Foreign Application Priority Data**

Nov. 22, 2013 (KR) 30-2013-0058954

(51) **LOC (10) Cl.** **14-04**

(52) **U.S. Cl.**

USPC **D14/485**

(58) **Field of Classification Search**

USPC D14/485-495; 715/700, 702-703, 764, 715/864, 961-962

CPC G06F 3/048

(57) **CLAIM**

We claim the ornamental design for a multimedia terminal with graphical user interface, as shown and described.

DESCRIPTION

The sole FIGURE is a front view of a multimedia terminal with graphical user interface showing our new design. The broken lines shown in the drawing are included for the purpose of illustrating environmental structure and form no part of the claimed design.

1 Claim, 1 Drawing Sheet
